UNITED STATES PATENT OFFICE.

JAMES ALEXANDER SEMPLE, OF CHICAGO, ILLINOIS.

FUEL VAPORIZER FOR EXPLOSIVE ENGINES.

Application filed April 1, 1922. Serial No. 548,871.

The object of this invention primarily is to provide means for supplying to an internal combustion engine a fuel in true vapor form, it being also an object to utilize that vapor which always forms in the fuel tank from natural evaporation and is ordinarily allowed to escape.

Briefly the invention resides in a container having connection with the liquid fuel tank for an explosive engine, through which air is adapted to be drawn as by the suction of the intake stroke of the engine whereby evaporation of liquid fuel is brought about and a true vapor is carried to the engine. In its preferred form the device itself is adapted to receive fuel in liquid form over which the air is drawn for evaporation of the fuel, and is also provided with connection with the top of the fuel tank for withdrawing from said tank the fuel vapor which has there formed by natural evaporation. These true vapors are conducted to the engine to improve the explosive values of the explosive charge.

In the drawings wherein certain embodiments of the invention are disclosed,

Fig. 1 is a vertical section through one form of the device;

Fig. 2 is a plan thereof as indicated by line 2—2 of Fig. 1 with parts broken away;

Fig. 3 is a cross section through a valve construction taken on line 3—3 of Fig. 1;

Fig. 4 is a vertical section through a modified form of the device;

Fig. 5 is a diagrammatic elevation showing the assemblage of the device with the engine;

Fig. 6 and Fig. 7 indicate different connections of the device of Fig. 1 with the fuel tank;

Fig. 8 is a sectional detail of a modified form of air intake for the container.

In the form of Figs. 1 and 2, the vaporizer comprises a casing or container 10 in which a head or cover 12 is set and secured as by screws 13. A duct 14 mounted in said head has its upper end connected with the bottom of the fuel tank T while a hollow boss 15 on the other side of the head having a passage 16 therein serves as a continuation of said duct for supplying said container. Boss 15 also has a seat 17 for the point 18 of a needle valve 19 operated by a float 20 for controlling the passage of liquid through the duct from the tank T. The stem of valve

19 is irregular in cross section as seen in Fig. 3 for passage of liquid from aperture 16 and for guidance of the valve by the interior walls of the boss 15. A pair of separating screens 22 are positioned above the lower-most extremity of the boss 15 and between the float chamber and the cover 12, thus defining a chamber above said screens.

A valve housing 24 for a ball check 25 operated by a spring 26, is threaded into the cover 12 with its lower or discharge end terminating in the float chamber below the screens. Cover 12 also carries a coupling 28 for connection of a vapor conduit 30 for conducting the vapor to the engine.

In the form of Fig. 6, the duct 14 is mounted in a fitting in the bottom of tank T and a stand pipe 34 whose lower end is also secured in said fitting extends up and opens into the top of the tank for taking off vapor only. As a substitute for the tank connection of Fig. 1, that of Fig. 7 may be employed where the device is secured to the lower end of the usual sediment bulb 35 from which the fuel line leads to the carburetor as indicated at 36, a drain cock 56 being used at the bottom of casing 10 if desired.

In the form of Fig. 4, the casing 10 is elongated and has an intermediate section 110, said casing being beaded circumferentially above said section 110 at 40 and below at 42, the latter bead assisting the positioning and retention of a plurality of separating screens 122. The bead 40 retains a fuel cup 44 in the top of the casing 10 and this cup carries the cover 12. Cover 12 is provided with an external boss or neck 112 secured to the bottom of the fuel tank T through which neck liquid fuel flows into the cup 44. A stand pipe 45 secured to the bottom of said cup rises up through the neck 112 to the top of the tank T and is there provided with notches 46 for the free passage of fuel vapor, while its lower portion is tapered slightly to form a seat for the valve tip or needle 118 of the valve stem 119 operated by the float 20. The needle 118 controls the flow of liquid fuel through apertures 48 in said tapered portion, and at the same time permits the passage of fuel vapor from the upper portion of pipe 45 through a small duct or passage 47 in the needle. Preferably the duct 47 is small enough to hinder free flow of liquid fuel through it in the event that a small amount of liquid

105
100
105
110

should enter the pipe 45 as by slopping over the top thereof when the tank is full, but on the other hand said duct is large enough so that liquid will be drawn through it by the 5 suction of the engine more or less readily in order to empty the pipe 45 of any collected liquid at least as rapidly as it is evaporated in the container 10 and yet avoid flooding the device. However, since the pipe 45 will 10 ordinarily be quite small and merely notched or similarly formed at its upper end, being designed for vapor passage only, very little liquid will enter it even when the tank is full, and no liquid will enter after the level 15 drops appreciably. Thus under nearly all conditions vapor will pass freely through the valve when the device is under suction.

For controlling the movement of liquid fuel and vapor, a partition 49 depends from 20 the bottom of cup 44 to the screens 122 and on one side a pair of small screens 50 are horizontally disposed. Thus, in addition to the liquid fuel chamber within cup 44, the container is divided into a receiving chamber 25 51, a float chamber 52 below screens 122, a vapor chamber 53 between screens 122 and 50, and a discharging chamber 54 from which the vapor is taken through conduit 30 connected to a fitting 55. Air which may be 30 required in addition to that drawn through pipe 45 with the vapor from tank T, is admitted into receiving chamber 51 through a valve housing 24 having a ball check 25 and threaded into cover 12 as in the other 35 form, its lower end being passed through and sealed in the bottom of cup 44.

Either form of the device may be connected up with the engine in any desired manner, but that indicated in Fig. 5 is preferred. Here the vapor conduit 30 leads to a 40 humidifying device D which receives moisture through a line 60 preferably in the form of air and steam taken from the top of the radiator R. Humidified air and fuel vapor 45 is drawn from the top of humidifier D through tube 62 into the intake manifold 64 of the engine or motor M by the suction of the engine.

In operation, the form of Fig. 4 admits 50 liquid fuel from cup 44 into chamber 51 past valve 118, vapor being drawn through duct 47 in the valve and air being drawn in past check valve 25. Mixing and vaporization takes place initially in chamber 51, being 55 augmented during passage through the three screens 122 which breaks up the liquid more or less. Surplus liquid collects in chamber 52 and operates float 20, the air and vapor being drawn across the liquid and up 60 through the screens 122, which here serve as separating screens, into chamber 53. The gas mixture then passes through the screens 50 which serve the double function of intercepting any particles of liquid which may 65 possibly have passed through screens 122,

and of preventing flame from being carried back into the various chambers in case of back-fire of the engine. The vapor is then drawn from chamber 54. In this form a drain cock 56 may be placed at the bottom 70 of the casing if desired.

In the other form, liquid fuel or vapor, as the case may be, is drawn through tube 14 past valve 18 into the float chamber, air being drawn when required past the ball 75 check valve 25 into the same chamber. The vapor is then drawn by the engine suction up through screens 22 into the chamber thereabove and thence out through conduit 30; the screens 22 serve to separate any liquid 80 particles. Even where tube 14 is connected up to take vapor from the top of the tank as in Fig. 6, it is preferable to use float 20 and its valve 18 to insure against flooding by splashing in the tank; incidentally any splashed liquid will increase the fuel vapor drawn from the device.

With either form various means may be employed for connecting the fuel line 36 leading to the carburetor. This may be as 90 in Fig. 7 as above described, or the line may be connected with the tank in the usual manner independently of the present device, or it may be connected with the present device. Where low grade fuel is used it may be 95 necessary to so connect said liquid fuel line as to guard against accumulation in the float chamber of non-volatile or difficultly volatile fuel. This is accomplished by connecting the line directly with the float chamber so that 100 a fresh supply of liquid fuel is being drawn constantly through said chamber, as shown in Fig. 4 at 36. As a result the air passing through the device will be brought into contact with a larger quantity of liquid than otherwise and more vapor will be formed. However, a plug 136 interchangeable with 105 the connection on line 36 may be provided on cup 44 so that liquid fuel may be taken directly from said cup if desired.

Thus it will be seen that I have provided means for supplying to an engine fuel in true vapor form, as distinguished from a mist or fine spray, whereby the explosions of the mixture supplied by the carburetor in the usual manner are materially bettered as regards fuel efficiency. At the same time I may use the vapor which naturally forms in the fuel tank above the level thereof. In any case where liquid fuel is to be taken into the container 10, the air admitted through the check valve 24 may be led by a small tube 124 to a point below the liquid level, as seen in Fig. 8, to assist the formation of fuel vapor.

I claim:

1. In combination, a liquid fuel tank, a container, a liquid connection between the tank and the container, said container having a liquid receiving chamber, finely per- 130

forated means above said chamber and below the point of liquid entry, said liquid passing through said means which thereby serves for breaking up the liquid entering said chamber, means for controlling the admission of liquid falling upon said perforated means, means for admitting air to said container above said perforated means, means for

directing air through said perforated means and into said chamber, and an outlet to 10 which vapor-laden air is drawn.

2. A structure according to claim 1 where-in a float-operated valve is employed as the means for controlling admissions of liquid.

In testimony whereof I affix my signature. 15
JAMES ALEXANDER SEMPLE.
